UNITED STATES PATENT OFFICE.

CHARLES H. KOSTER, OF NEW YORK, N. Y.

DESIGN FOR A DECORATIVE FABRIC.

SPECIFICATION forming part of Design No. 19,243, dated July 30, 1889.

Application filed July 3, 1889. Serial No. 316,445. Term of patent 7 years.

To all whom it may concern:

Be it known that I, CHARLES H. KOSTER, a citizen of the United States, residing at New York, in the county of New York and State 5 of New York, have invented and produced a new and original Design for Decorative Fabrics, of which the following is a specification.

The object of this design is to provide a novel decorative bunting; and the leading 10 features thereof consist in a longitudinal star-sprinkled stripe extending along one edge or margin of the fabric and bearing a series of figures arranged at intervals and representing the eagle, and transverse stripes 5 of alternately-contrasting colors, all extending from the inner edge of the longitudinal stripe.

The figure of the accompanying drawing is a plan view showing the design.

The letter a indicates the longitudinal stripe, 15 sprinkled with stars b and bearing a series of figures arranged at intervals and representing the eagle with wings displayed and grasping in its talons a sheaf of arrows or other national emblem. This stripe extends in a 25 right line along one edge of the fabric, and transverse stripes c d of alternately-contrasting colors all extend from the inner longitudinal edge e of the star-sprinkled stripe. The longitudinal stripe is of a color contrasting 30 with the color of the transverse stripes.

What I claim is—

The design for decorative bunting, consisting of the longitudinal star-sprinkled stripe a, extending along one edge or margin of the 35 fabric and bearing a series of figures arranged at intervals and representing the eagle, and the transverse stripes c d of alternately-contrasting colors, all extending from the inner edge of the longitudinal stripe, substantially 40 as shown and described.

In testimony whereof I have affixed my signature in presence of two witnesses.

CHARLES H. KOSTER.
